(57) **CLAIM**

The ornamental design for an end panel accessory, as shown and described.

DESCRIPTION

FIG. 1 is a perspective view of an end panel accessory showing visible environmental structure of an associated shelving unit in broken lines, according to an embodiment of the invention.

FIG. 2 is an additional perspective view thereof.

FIG. 3 is a partial perspective view thereof, showing visible environmental structure of a first billboard received in a right-hand side vertical extender and a second billboard secured to a face of a left-hand side vertical extender in broken lines.

FIG. 4 is a front view thereof.

FIG. 5 is a back view thereof.

FIG. 6 is a right end view thereof.

FIG. 7 is a left end view thereof.

FIG. 8 is a top view thereof.

FIG. 9 is a bottom view thereof; and,

FIG. 10 is a perspective view of an end panel accessory, according to a second embodiment of the invention, showing the end panel accessory without mounting holes and showing a right-hand vertical extender and a left-hand vertical extender in a second position, it being understood that the other views not shown are the same as those of the first embodiment.
